(57) **CLAIM**

We claim the ornamental design for a display, as shown and described.

DESCRIPTION

The present application claims priority under 35 U.S.C. section 120 from copending U.S. Patent Application Ser. No. 11/063,068 filed on Feb. 22, 2005 by Peter M. On, Glen Allen Oross and Francois Duval titled Display Base With Forward Facing Interconnect Panel and copending U.S. Patent Application Ser. No. 29/223,929 filed on Feb. 22, 2005 by Peter M. On, Glen Allen and Francois Duval, the full disclosures of which are hereby incorporated by reference.

FIG. 1 is a top perspective view of a display according to the present invention;

FIG. 2 is a front elevational view thereof;

FIG. 3 is a right end elevational view thereof;

FIG. 4 is a left end elevational view thereof;

FIG. 5 is top plan view thereof;

FIG. 6 is a bottom plan view thereof;

FIG. 7 is a rear elevation view thereof; and,

FIG. 8 is a partial front perspective view thereof illustrating a front panel of the display in an open position.

The broken lines in the drawings are for illustrative purposes only and form no part of the claimed design.
